DESIGN FOR A BLOUSE

Abraham M. Katz, Freeport, N. Y.

Application June 23, 1944, Serial No. 114,155

Term of patent 3½ years

(Cl. D3—25)

To all whom it may concern:

Be it known that I, Abraham M. Katz, a citizen of the United States and a resident of the town of Freeport, in the county of Nassau and State of New York, have invented a new, original, and ornamental Design for a Blouse, of which the following is a specification, reference being had to the accompanying drawing, forming a part thereof.

Fig. 1 is a front view of my blouse, showing my design, and

Fig. 2 is a rear view thereof.

I claim:

The ornamental design for a blouse, substantially as shown.

ABRAHAM M. KATZ.
